UNITED STATES PATENT OFFICE

165,571

COMBINED CABINET AND COUCH

Russell E. Brandenburger, Sr., Shelbyville, Ind.

Application August 17, 1951, Serial No. 16,325

Term of patent 14 years

(Cl. D33—19)

To all whom it may concern:

Be it known that I, Russell E. Brandenburger, Sr., a citizen of the United States, residing at Shelbyville, in the county of Shelby and State of Indiana, have invented a new, original, and ornamental Design for a Combined Cabinet and Couch, of which the following is a specification, reference being had to the accompanying drawing, forming part thereof.

The figure is a perspective view of a combined cabinet and couch, showing my new design. The opposite end and back are plain.

I claim:

The ornamental design for a combined cabinet and couch, as shown and described.

RUSSELL E. BRANDENBURGER, Sr.
